(57) **CLAIM**

The ornamental design for a plastic container, as shown and described.

DESCRIPTION

FIG. 1 is a top, rear, left side perspective view of a plastic container showing our new design;

FIG. 2 is a left side elevational view of FIG. 1;

FIG. 3 is a right side elevational view of FIG. 1;

FIG. 4 is a rear elevational view of FIG. 1;

FIG. 5 is a front elevational view of FIG. 1; and,

FIG. 6 is a top plan view of FIG. 1.

The broken lines shown in the drawings illustrate portions of the plastic container that form no part of the claimed design.
